UNITED STATES PATENT OFFICE

LEVI MARSH, OF SOUTH ADAMS, MASSACHUSETTS.

IMPROVEMENT IN ASH-SIFTERS.

Specification forming part of Letters Patent No. **144,466**, dated November 11, 1873; application filed July 19, 1873.

To all whom it may concern:

Be it known that I, LEVI MARSH, of South Adams, in the county of Berkshire and State of Massachusetts, have invented a new and useful Improvement in Ash-Sifter, of which the following is a specification:

Figure 1 is a vertical longitudinal section of my improved ash-sifter, taken through the line $x x$, Fig. 2. Fig. 2 is a top view of the same, the cover being removed. Fig. 3 is a detail view of the fastening for the sieve-door.

Similar letters of reference indicate corresponding parts.

My invention has for its object to furnish an improved ash-sifter which shall be so constructed that the coal may be sifted without the escape of the fine ashes through the room, and which shall at the same time be simple in construction and convenient in use. The invention will first be fully described, and then pointed out in the claim.

A is the box, which is provided with a close cover, B, and is supported upon legs C, of such a length that an ash-pail or coal-scuttle may be placed beneath the bottom of the box A to receive the ashes, which are allowed to escape through a hole in the bottom of the box A, by drawing out the slide D. In one end of the box A is formed a spout, E, through which the coal may be allowed to escape by drawing up the slide F. The inner end of the spout E projects into the box A, and its outer end projects sufficiently to allow a coal-scuttle or other receptacle for the coal to be placed beneath it. G is the sieve, the forward end of which is provided with a door, g' , hinged at its upper edge to a cross-bar attached to the forward part of the upper edges of the ends of the sides of said sieve. The door g' is fastened shut by a bolt or other fastening, H, which catches upon a catch attached to a bar attached to the forward part of the lower edges of the sides of said sieve. I is a spring, one end of which is attached to the top bar of the forward end of the sieve G, and its other end to the door g' , and which, as soon as the fastening H is released, throws open the door g' and allows the coal to escape from the sieve into the spout E. The rear part of the sieve G rests upon a bar,

J, attached to the box A, as shown in Figs. 1 and 2. The sieve G is further supported by the rod K, to which it is attached. One end of the rod K is pivoted to one side of the box A, and its other end passes through a slot in the opposite side of the box A, and has a handle attached to it for convenience in operating the sieve. The rod K also passes through a plate, L, which is placed upon the outer side of the box A, over the slot in said box, and slides in keepers attached to the box, so as to prevent any ashes from escaping through the slot in which the rod K works. M is a long pin, which is slipped in through a hole in the side of the box A, so as to pass above the rear part of the sieve G, and prevent the said sieve from tipping before the said pin is withdrawn.

In using the sifter, the ashes and coal to be sifted are poured into the sieve G, and the handle of the rod K is moved back and forth quickly. When the ashes have been all shaken out, the slide F and the pin M are withdrawn, and the handle of the rod K is turned slightly, causing the forward end of the sieve G to drop. As the forward end of the sieve G descends, the fastening H comes in contact with the inner end of the spout E and becomes unfastened, thus allowing the coal to escape through spout E into the receptacle placed beneath said spout. As soon as the coal has been discharged, the slide F is inserted, and the sifter allowed to stand until the ashes have all settled. The slide D is then withdrawn and the ashes allowed to escape into the receptacle placed beneath the sifter. The door g' is then refastened, the pin M inserted, and the sifter is again ready for use.

Having thus described my invention, I claim as new and desire to secure by Letters Patent—

The combination of the rod K, sliding plate L, pin M and bar J with the sieve G and box A, substantially as herein shown and described.

LEVI MARSH.
